UNITED STATES PATENT OFFICE.

ALEXANDER BLOCK, OF NEW YORK, N. Y.

LOCK.

1,422,820.

Specification of Letters Patent. Patented July 18, 1922.

Application filed September 9, 1920. Serial No. 409,067.

To all whom it may concern:

Be it known that I, ALEXANDER BLOCK, a citizen of the United States, residing at New York city, in the county of New York and 5 State of New York, have invented certain new and useful Improvements in Locks, of which the following is a specification.

This invention relates to locks, and more particularly to locks of the type disclosed in 10 my co-pending applications, filed July 13, 1920, Serial No. 395,890; and April 6, 1920, Serial No. 371,737.

The principal object of the present invention is to improve the locking mechanism, by 15 providing suitable and efficient means for moving the multiple headed bolt into engaging position and for locking said bolt against reverse movement from such position. This is accomplished in my co-pending application 20 of July 13th by means of a cam upon a shaft rotatable by means of key-operated mechanism. Said cam when operated moves the hooked bolt into locking position and subsequently thereto moves said bolt into engaging position, and dogs the bolt in such 25 position. Reverse movement of the bolt is prevented by said cam, reverse revoluble movement of the cam being prevented by the ward pins of the cylinder lock or other key 30 operated mechanism that may be employed. In my previous invention the strain of maintaining the bolt in its varying positions is placed upon the pins of the cylinder lock. This is obviated in the present invention by 35 providing the lock with two bolts and a cam. One of said bolts, is, as in the previous invention, a multiple-headed bolt, and the other, which I designate an actuator bolt is arranged to move primarily in a direction 40 for moving the multiple-headed bolt into engaging position, and then to continue its movement longitudinally into locking position. The cam in the present invention is of such construction that when operated, it 45 moves the hooked bolt longitudinally, and as it continues its revoluble movement it forces said actuator bolt to first move in a direction for projecting the hooked bolt into engaging position and then to continue the movement 50 of said actuator bolt longitudinally into locking position and in supporting relation to said hooked bolt. It is obvious that such construction as shown in the present invention relieves the pins of the strain imposed upon them in the previous invention, and locks the hooked bolt in its projected po-

sition far more securely than could be accomplished by the pins. A further advantage of such a construction is that the two bolts when occupying their extreme operative positions, fill the entire opening of the keeper, and thereby prevent displacement of the locking mechanism in a vertical direction, and this coupled with the impossibility of displacing the bolts in a longitudinal direction affords complete protection against attempts to force open a door through the instrumentality of a jimmy or other instrument designed to dislocate the locking mechanism with burglarious intent.

Another object of the present invention is to eliminate from the locking mechanism all springs, pawls, carriers and other actuating devices commonly employed in locks, by providing a cam of such construction that it will 70 efficiently actuate said bolts in the above-described manner, and dog said bolts in their operative or inoperative positions. Such construction is conducive to greater efficiency of operation, renders the locking mechanism less likely to get out of order, and cheapens the manufacturing cost of the lock. Furthermore, the type of lock described herein, employed in connection with 75 my improved keeper disclosed in my co-pending application #390,411, filed June 21st, 1920, and with my improved cylinder lock disclosed in co-pending application #374,107 filed April 15, 1920, provides a 80 complete burglar-proof locking combination 85 for a door. It is understood, however, that the lock described herein may be used in connection with any other type of keeper of suitable construction, and the key-operated mechanism may be of a construction other 90 than that shown herein.

A further object is to provide improved key-operated mechanism to operate said cam for actuating the above-mentioned bolts, said mechanism being arranged to prevent reverse revoluble movement of the cam, and thus reverse movement of the bolts, except by the instrumentality of said mechanism.

The construction of the parts shown herein is to be taken as illustrative and not as defining the limits of the invention.

The above-mentioned type is the preferred type. A modification thereof is also shown and described below, comprising a multiple headed bolt mounted for both slideable and 110 pivotal movement on a shaft. A cam upon said shaft is arranged to move said bolt

longitudinally and to subsequently project said bolt into engaging position. This is more properly a modification of the type disclosed in my application filed July 13th, as the strain for maintaining the bolt in projected position is placed on the pins of the key operated mechanism, whereas in the preferred type shown herein absolutely no strain is borne by the pins, the said actuator bolt affording powerful and unyielding means for locking the bolt with multiple heads against reverse movement from its engaging position.

Further objects and advantages will appear in the specification shown herein.

The preferred and modified types of lock embodied in my invention are shown in the accompanying drawing, wherein, Figure 1 shows a sectional elevation of the lock showing the disposition of the locking mechanism when in the unlocked state, and in broken lines showing part of the multiple-headed bolt in locking position prior to its movement into engaging position. Figure 2 shows the disposition of the mechanism with the hooked bolt in engaging position and the actuator bolt in locking position and in supporting relation with reference to said hook bolt. Figure 3 is a view of the hooked bolt shown in the above figures. Figure 4 shows the cam partly in section on a line A—A in Figure 1. Figure 5 shows a cross-section of the lock on a line B—B in Figure 2. Figure 6 shows an edge view of the actuator bolt. Figure 7 is an elevation of the actuator bolt broken across. Figure 8 is a cross-section thereof. Figure 9 is a longitudinal sectional view of the lock on a line A—A in Figure 2. Figure 10 is a sectional view of the face plate of the lock casing, parts broken away, and showing a broken off section of the shaft, and recesses for housing a device for restricting the movement of the spindle key in and out of the lock body and for throwing the locking mechanism out of operation. Figure 11 is a member of said device. Figure 12 is another view of same. Figures 13 and 14 are two other members of said device. Figure 15 shows the key plug and the shaft for mounting the cam, and the manner in which said key plug and said shaft are connected for longitudinal adjustment. Figure 16 shows a broken off section of the face plate of the lock casing and a sectional view of the above-mentioned device. Figure 17 shows a view of the inner face of said shaft. Figure 18 shows an elevation of the spindle key broken across. Figure 19 is a cross-section thereof on a line B—B. Figure 20 is a cross section of said key on a line A—A showing the adjustable slide and spring thereon. Figure 1^A is a sectional elevation of the modified type of lock, showing the disposition of the mechanism when in the unlocked state.

state. Figure 2^A shows same with the mechanism in completely locked state. Figure 3^A is the same with the bolt in locking position prior to being moved into engaging position. Figure 8^A is a longitudinal section of the lock on a line A—A in Figure 2 and B—B in Figure 2^A. Figure 9^A is an elevation of the plate attached to the inner extremity of the rotatable key plug, showing the spring attached thereto. Figure 10^A shows a longitudinal section of the key plug and an edge view of said plate with the spring attached thereto. Figure 11^A shows the spring. Figure 12^A is the spindle key. Figure 13^A is an edge view thereof. Figure 14^A is a pin key. Figure 15^A shows a section of the lock casting, the shaft and the device for throwing the locking mechanism out of operation.

I will now take up the description of the preferred type of lock embodied in my invention, as shown in Figures 1 to 20. The lock casing a is of the usual or any suitable construction, and contains a multiple-headed hooked bolt c , an actuator bolt d and a cam h for actuating said bolts. Hooked bolt c comprises a locking projection or head c^1 carrying hooked bolts c^2-c^3 on its outer or locking end. The shank portion c of said hooked bolt may embrace a longitudinal slot c^6 ending in a slot c^7 preferably vertically disposed thereto; a groove c^4 on said shank c may run in a vertical direction to said slot c^6 ; another groove c^9 on said shank; and a grooved ledge c^8 projects from said shank and affords movable connection of said shank with said actuator bolt d ; c^5 designates a stud in said shank portion of bolt c .

Actuator bolt d is provided with a locking projection d^1 on its outer or locking end; a groove d^2 , which may be a slot; studs d^3 and d^4 , and a grooved ledge d^5 projecting from said actuator bolt for engagement of said actuator bolt with said hooked bolt and affording movable connection between them. 110

The cam h is mounted upon a rotatable cylinder or shaft j having a keyway j^3 . The cam describes the greater part of a circle which is concentric with said rotatable cylinder. The cam has a **U** shaped cut out at one side, one of the legs of the **U** being preferably shorter than the other, and having a stud h^3 preferably in the extremity of the shorter leg and a stud h^2 preferably in the extremity of the longer leg of said **U**. In its normal rest position, cam h has its **U** cut out embracing stud c^5 in the bolt c , stud h^3 lying in the mouth of groove c^4 on said hooked bolt c , and stud h^2 not in operative association with any element either on hooked bolt c or on actuator bolt d . 120 125

Studs g and g^1 in the casing are in opera- 130

5 tive association with hooked bolt *c* and are adapted to guide the movement of said hooked bolt in a longitudinal direction, and when said hooked bolt is moved into engaging position, said groove *c*⁹ receives stud *g* in the casing, and stud *g*¹ is made to lean against the rear edge of the bolt *c*. To the end that said studs *g* and *g*¹ guide and prevent vertical displacement of the hooked 10 bolt during its longitudinal movement, and being brought into engaging position with said bolt *c* during the movement of said bolt into engaging position, said studs act to prevent reverse movement of said bolt in a reverse 15 longitudinal direction.

The casing is also provided with grooves *e* and *f* in operative association with the actuator bolt *d*, which said grooves are adapted to guide primarily in a direction for 20 moving the hooked bolt into engaging position subsequently to the movement of said hooked bolt into locking position, and after thus actuating said hooked bolt, to continue its movement in a longitudinal direction into 25 locking position and in supporting relation with reference to said hooked bolt. The said grooves *e* and *f*, preferably on the casing, may be obliquely disposed on the casing and parallel to each other. Said grooves *e* and *f* 30 terminate at one end in longitudinal grooves *e*¹ and *f*¹ respectively, and at the other end the said oblique grooves terminate in longitudinal grooves *e*² and *f*² respectively; said longitudinal grooves *e*¹ and *f*¹ being in alignment with each other, and grooves *e*² and *f*² 35 being in alignment with each other. The longitudinal grooves on the casing are so positioned that the distance between longitudinal grooves *f*¹ and *f*² is approximately 40 equal to the length of the hooks on the hooked bolt, and likewise with slots *e*¹ and *e*². Studs *d*³ and *d*⁴ are normally taken into longitudinal slots *f*¹ and *e*¹ respectively, when said actuator bolt is in normal rest 45 position. To the end that after the cam moves the hooked bolt longitudinally, the stud *h*² of said cam enters groove *d*² on the actuator bolt *d*, and as said cam continues to move revolutely, said stud *h*² 50 forces actuator bolt *d* to move toward its locking position; the obliquely disposed grooves *e* and *f* first guiding said actuator bolt through its studs *d*³ and *d*⁴ in a direction both vertical and longitudinal for moving 55 the hooked bolt into engaging position, and as studs *d*³ and *d*⁴ enter into longitudinal slots *e*² and *f*² said actuator bolt continues to move only in a longitudinal direction and into supporting relation with reference 60 to said hooked bolt.

The cam *h* is mounted upon a shaft *j* having a keyway *j*³. Hooked bolt *c* is adapted to move first longitudinally on said shaft *j* as a guide until it reaches its locking position and subsequently thereto to move verti-

6 cally into engaging position along said shaft as a guide. Slot *c*⁶ in said hooked bolt with its vertically disposed branch slot *c*⁷ allows of the movement of said hooked bolt in the above-mentioned directions on said shaft as 70 a guide. The diameter of said shaft *j* is preferably equal to the width of said slots.

When the cam *h* is operated by shaft *j*, stud *h*³ in the cam moves in and out of groove *c*⁴ in bolt *c*, and in its movement in and out of said groove forces hooked bolt *c* to move into locking position. The direction taken by said cam when so operated is indicated by arrows *k* and *k*¹. While said stud *h*³ lies in groove *c*⁴ and during its movement in and 75 out of said groove, the said stud acts to prevent reverse movement of said bolt from any position to which said cam had delivered it. Subsequently to the movement of said hooked bolt into locking position, however, 80 stud *h*³ leaves groove *c*⁴ and the function of dogging the bolt is assumed by the circular edge of the cam leaning against stud *c*⁵ in the casing. Said stud *c*⁵ is so positioned that during the entire revoluble movement 85 of the cam subsequently to the evacuation of groove *c*⁴ by stud *h*³ in the cam, the said cam is adapted to lean against it and prevent reverse movement of the hooked bolt from its locking position. During the move- 90 ment of said hooked bolt longitudinally by said cam, stud *h*² is carried by projection *h*¹ in the direction of arrows *k*, and is delivered into engagement in groove *d*² in actuator bolt *d* preferably simultaneously with 95 the arrival of said hooked bolt into locking position. As the cam continues subsequently to move revolutely, stud *h*² moves into said groove *d*² and forces actuator bolt *d* to move longitudinally and vertically, being guided to move in said two directions by 100 grooves *e* and *f* on the casing, and said actuator bolt being in movable operative connection with the hooked bolt, causes said hooked bolt to move vertically into engaging position, and then the said actuator bolt continues to move longitudinally into its locking position, being guided in its movement by longitudinal grooves *e*² and *f*² on the casing. In such locking position, the 105 locking projection *d*¹ on said actuator bolt *d* fills in the gap left when hooked bolt *c* is moved into engaging position, and thereby locks said hooked bolt against reverse movement from such position. The stud *h*² in projection *h*¹ on cam *h* now occupies a position in groove *d*² on actuator bolt *d* as shown in Figure 2, and acts to prevent reverse movement of said actuator bolt from its locking position except by the reverse 110 115 movement of said cam *h*, which is controlled by key operated mechanism. It is evident that the hooked bolt is thus securely and powerfully locked against reverse movement in a vertical direction by the locking 120 125 130

projection of the actuator bolt, and is securely locked against reverse longitudinal movement, firstly by plates b^1 and b^2 in keeper b ; secondly by stud c^5 in the hooked bolt leaning against cam h , and studs g and g^1 in the casing with which said bolt is made to engage as it moves into engaging position in the keeper. Such a combination of locking elements, it is quite obvious, forms an effective and powerfully unyielding barrier to one who attempts to force the lock through the instrumentality of a jimmy or other instrument with burglarious intent.

The actuator bolt d normally occupies the position shown in Figure 1, with its studs at the bottom of the obliquely disposed grooves in the casing. During the movement of the hooked bolt into locking position, said actuator bolt continues to occupy its normal rest position, firstly because it is movably connected with said hooked bolt; secondly because upward displacement of the hooked bolt is prevented by guide studs g and g^1 , thus preventing the movement upward of said actuator bolt which direction it must first take in said oblique grooves in the casing before it can move longitudinally. When the hooked bolt is delivered into locking position, groove c^9 on said hooked bolt is delivered into alignment with stud g in the casing, and the inner extremity of said bolt occupies a position directly in front of stud g^1 in the casing. It is thus seen that the position of the bolt now allows of its movement in a vertical direction. Now as the actuator bolt is moved by the cam, and as said actuator bolt is in loose operative connection with said hooked bolt, the first impulse of said actuator bolt is to move along oblique grooves e and f , being guided in its movement by its studs which are taken into said grooves. This causes the actuator bolt to move hooked bolt e vertically until it reaches its engaging position. The actuator bolt d now occupies a position with its studs at the upper extremities of the obliquely disposed grooves, and the locking projection d^1 of actuator bolt d filling the gap left in the opening in the lock casing by the movement of the hooked bolt vertically into engaging position. As the cam completes its revolute movement, the actuator bolt moves longitudinally, being now guided in its movement by its studs in longitudinal branch grooves e^2 and f^2 , until it reaches the locking position shown in Figure 2.

Slot c^6 is of a length sufficient to allow of the complete movement of the hooked bolt in and out of the casing, and its vertical branch c^7 sufficiently long to allow of its complete vertical movement into and out of engaging position.

Taking up the modified type of lock as shown in Figures 1^A to 15^A, I will describe it in brief to show the underlying differences

between this type and the preferred type described above. The locking mechanism of the modification comprises a hooked bolt and a cam, omitting the extra actuator bolt in the preferred type. Casing 1 contains modified bolt 2, having a locking projection 3 and hooked bolts 4 and 4^A on its outer end. A shaft 6 having a keyway 7^A for holding a spindle key 8, affords mounting to bolt 2; said shaft running through a slot 16 extending longitudinally in said bolt 2. 15 designates a groove in the bolt, 14 a stud, and 13^B another groove. The hooked bolt 2 is adapted to move in and out of the casing along said shaft as a guide and when moved into locking position it is arranged to be projected into engaging position on said shaft as a pivot. Slot 16 in this type has no vertical branch slot as in the preferred type. A cam 5 is mounted upon the shaft 6 and is adapted to move revolubly when the shaft is rotated by means of key operated mechanism or otherwise. Cam 5 is circular in shape, having an outer edge describing for the most part the arc of a circle concentric with the shaft 6. Cam 5 has a U shaped cut out, one leg of the U having a stud 8 near its extremity, and the other leg of said U having a projection or heel 9 at its outer end, when in normal rest position, the U cut out embraces stud 14 in the bolt, with stud 8 in the cam lying in the entrance to groove 15 in the bolt. 13^A is a stud in the casing adapted to be received in groove 13^B in the bolt. 13 designates a stud also in the casing and adapted to limit the upward movement of said bolt. When cam 5 is operated, stud 8 in the cam moves in and out of the groove 15 and causes the bolt 2 to move into locking position. Stud 8, then leaving the groove, the cam continuing its revoluble movement constantly leans against stud 14 in the bolt, and acts to prevent reverse movement of the bolt from its locking position. When said cam 5 has nearly completed its revolution, projection 9 encounters stud 14 in its upward sweep, bears against said stud and forces the bolt into engaging position. Reverse movement of said bolt from such position cannot be obtained except by reverse movement of the cam, and such reverse movement of the cam is obtained only by the operation of the key operated mechanism. It is evident then that the function of maintaining the bolt in its projected position lies with the key operated mechanism, the strain being borne entirely by the pins of the cylinder lock.

It must be clearly understood that I do not mean to limit myself to the minor details of construction as shown and described above in the preferred type and its modification. It is conceivable that slight changes in the structure may be made with-

out departing from the spirit of the invention. For instance, a groove may be replaced by a slot, or vice versa; or the studs and grooves may be interchanged—the element having the grooves may have studs and the element having the studs may have the grooves, to accomplish the same purpose for which they are intended in the present invention. The above description gives only a conception of the invention in forms which I prefer, and it is evident that minor changes may be made that could not constitute a new invention.

The key operated mechanism shown in Figures 8^a and 9 may be applied to either of the types shown and described herein. My preferred type of key operated mechanism is that shown in Figures 9 to 20. The present invention is an improvement upon the type of cylinder lock disclosed in my co-pending application filed April 15, 1920, Serial No. 374,107. The changes made adapt said cylinder lock for use in connection with the improved springless and pawl-less locking mechanism employed in the above-described types of locks.

The cylinder lock comprises a tumbler barrel casing C having a rotatable key plug K; said plug having a keyway K¹. A flange K³ on the outer end of the key plug fits into a grooved collar in casing C and prevents inward displacement of said rotatable key plug, and a collar K⁴ preferably fastened to the key plug by means of a screw, about its inner extremity, prevents outward displacement of said key plug. Projecting from its inner extremity, said plug may have two tongues K² for affording adjustable connection between the cylinder lock and the locking mechanism.

Lock casing a has or may have a removable plate a³ which is or may be provided with a cylindrical member or bearing 100 having an inwardly extending flange W¹. Tumbler barrel casing C is provided with an outwardly extending flange W and is connected with said cylindrical member 100 for longitudinal adjustment. Cylindrical member 100 has an inner and an outer opening. Its inner opening is normally covered by a plate 20 which may be attached to removable plate a³ by means of screws 20^a. A shaft j is or may be journaled at its outer end in a bearing a⁵ in casing a and at its inner end in a bearing in said covering plate 20. Said shaft j may be provided with a flange j¹ on its outer extremity fitting in a grooved collar in bearing a⁵ for preventing inward displacement of said shaft, and a collar j⁴ which may be fastened near the inner end of said shaft by means of a screw, for preventing outward displacement of said shaft. As shown, the cylinder lock C is arranged to slide within cylindrical member 100, and their flanges are adapted to engage when the

cylinder lock is moved outwardly, said flanges thus operating to prevent removal of the cylinder lock from the cylindrical member of the casing through its outer opening.

The cylinder lock is thus connected with said casing for longitudinal adjustment for varying thicknesses of doors. The adjusting device comprises a machine screw or screw bolt s, the head portion of which is journaled in a bearing in said covering plate 20, and having a collar s¹ for preventing independent movement longitudinally of said screw. The threaded portion of said screw is arranged to be received in a threaded bearing in flange W of tumbler barrel 80 casing C. It is evident that when screw s is operated by means of a screw driver or other suitable instrument, cylinder lock C is caused to move longitudinally within cylindrical member 100, and the adjustment can thus be made from the inner aspect of removable plate a³ or rather covering plate 20 for different thicknesses of doors. In assembling the lock for attachment to a door, the cylinder lock is introduced with its outer extremity first, through the inner opening of the cylindrical member 100, and is passed through the outer opening of the cylindrical member. Screw s in covering plate 20 is then screwed a distance into flange W 95 of cylinder lock C, and covering plate 20 is attached by means of screws 20^a to removable plate a³. A hole is then cut in the door D of a size large enough to admit cylindrical member 100. The cylindrical member and the cylinder lock are then inserted into said hole in the door, until removable plate a³ is flush with the door. Then by turning the screw with a screw driver in the desired direction from the inner side of said covering plate 20, the longitudinal adjustment is easily made for that particular door. The removable plate and said cylinder lock are now withdrawn from the hole in the door, the plate is attached to the lock body by means of a screw or other suitable means, and the entire combination may now be applied to the door and fastened thereto by any suitable means. An escutcheon plate P is provided for covering up the outer opening in the door, exposing to view only the rotatable key plug into which the pin key must be inserted for operating the locking mechanism.

The spindle usually employed for effecting operative connection between the rotatable key plug and the locking mechanism is replaced in the present invention by improved means shown herein. Through the entire length of shaft j runs a keyway j³ for a spindle key 7. Near its inner end and extending for some distance in the shaft j, said shaft is provided or may be provided with slots j² preferably vertically disposed to said keyway j³; said slots j² being adapted to re-

ceive tongues k^2 on the inner extremity of tumbler barrel K. Said tongues and said slots are of such length that they will maintain the operative connection between the 5 tumbler barrel K and shaft j for any longitudinal adjustment of the cylinder lock and cylindrical member 100 that may be made for any door. Said tongues K² of tumbler barrel K are arranged to move longitudinally 10 in slots j² during the longitudinal movement of casing C in cylindrical member 100, but when they are moved revolvably by rotating the tumbler barrel K, they are adapted to cause shaft j to rotate for operating the 15 locking mechanism. It is obvious that when the tumbler barrel is locked, shaft j will be locked against revolvable movement, and thus the locking mechanism will be locked against reverse movement from whatever position 20 they might have been delivered to during the operation of said cylinder lock.

The cylinder lock is or may be, as usual, operated by means of a pin key from the outside of the door for operating the locking 25 mechanism. From the inside of the door however, the locking mechanism is usually operated by means of a knob and an extra cam, necessitating the employment of pawls and springs for maintaining the locking 30 mechanism in operative or inoperative positions. In the present invention however, the springless and pawl-less locking mechanism and the improved construction of said mechanism precludes the necessity of and renders 35 undesirable the employment of a knob and an extra cam for operating the locking mechanism from the inside of the door. I therefore employ a key 7 of specific construction, and which I designate a spindle key. 40 Said spindle key is or may be arranged normally to be maintained as a fixture in the lock body, being mounted in shaft j, passing through a keyway j³ in said shaft, and arranged to move longitudinally within said 45 shaft and into key plug K for unlocking said plug and operating same and to simultaneously rotate the shaft for operating the cam and thus actuating the locking mechanism.

The type of spindle key shown in my application of July 13th, and the one shown in the present invention in Figures 8^A and 12^A, is intended to remain as a permanent fixture within the lock, and is not removable entirely, being only movable a distance in and 55 out of the lock casing for operating the cylinder lock and the locking mechanism. Were said spindle key to be removed entirely, operation of the tumbler barrel by means of a pin key inserted from the outside, 60 would fail to operate the locking mechanism which would thus remain in the state in which it happened to be at the time.

The type of construction shown in Figure 9 and described above, allows of the complete removal of the spindle key when de-

sired or required. This feature adds considerably to the further protection of a door against burglarious attempts to gain admission. It is commonly known that when burglars cannot readily force open a door 70 through the instrumentality of jimmying the bolt or keeper, particularly on doors having glass or thin wooden panels, they cut or break an opening in said panel near the knob or key projecting from the lock body on the 75 inside of the door, and then introducing the hand or an instrument, turn the knob or key and thereby operate the locking mechanism and gain admission. In the preferred 80 type of construction in the present invention as shown in Figure 9, it is possible to avoid such a contingency by entirely removing said spindle key from the lock body, and because of the loose connection between the tumbler barrel and the shaft for operating the locking mechanism, a pin key inserted from the outside into said tumbler barrel will operate said tumbler barrel and likewise the locking mechanism. This operates as a considerable advantage particularly 85 when the lock is applied to doors entering into stores or buildings or apartments safeguarding valuables. Should the burglar break a glass panel or drill a hole in the wooden panel, he will not be able to gain 90 admission by operating the lock in the above-described manner. The only way for operating the locking mechanism is by means of a key that will unlock and operate the cylinder lock.

The spindle key 7 as shown in Figure 18, is however, intended to be normally partly confined within the lock body, a portion projecting therefrom for the purpose of manipulating the key when required to operate the locking mechanism from the inside. Means are provided for restricting its movement in and out of the lock body—inwardly, to a distance sufficient to allow of the unlocking of the tumbler barrel and operation of 105 same for operating the locking mechanism; and outwardly, a sufficient distance for allowing of the insertion of the pin key from the outside into said tumbler barrel for operating the locking mechanism from the 110 outside of the door. With these objects in view, spindle key 7 is provided with a bitted member sk, a spindle portion 7 and a head or thumb member 7^a for manipulating said key. Running longitudinally in spindle portion 7 is or may be a groove or slot 7^t, which is adapted to receive a spring-pressed 115 pin for restricting its movement outwardly to a distance sufficient to allow of the insertion of a pin key in the tumbler barrel 120 from the outside, and for restricting the movement of said key in the direction into the tumbler barrel to a distance not sufficient 125 for operating the tumbler barrel and therefore preventing the operation of the locking 130

mechanism. The reason for this arrangement is this: Although an extremely and well-nigh impossible operation, a burglar possessing inordinate skill and patience 5 might introduce a delicate instrument into the key plug, and seizing the inner end of the spindle key, draw said key into the tumbler barrel and thereby unlock said barrel and be able to operate the locking mechanism. The present construction of the spindle key and the spring pressed pin normally received within said groove 7^t precludes the possibility of such an operation. Should the burglar succeed in seizing the 10 spindle key, he will be able to draw it into the tumbler barrel only a limited distance—a distance not sufficient for operating the cylinder lock and thus will fail to operate the locking mechanism.

15 After operating the locking mechanism by means of said spindle key, the key must be withdrawn a distance from the lock body to allow of the re-engagement of said spring-pressed pin in the groove 7^t of said spindle key. Should the key be inadvertently left full length in said tumbler barrel, the barrel would remain unlocked and would be operable from the outside without the use of a key—that is, the pin key required for operating 20 the cylinder lock from the outside. Any one could then operate the locking mechanism from the outside with any small instrument that will rotate the key plug. To obviate this emergency and to correct 25 such a drawback, I have provided said key with an adjustable device for automatically withdrawing said spindle key from said tumbler barrel a distance sufficient to allow of the re-engagement of said key by means 30 of its groove 7^t with pin n , for restricting the movement of said key into the tumbler barrel. Said adjustable device comprises 35 preferably a slide q and a spring r attached thereto, and which may be of rectangular 40 shape as shown in the drawing Figure 19. Said slide is movably mounted on the spindle portion 7 of said spindle key, and may be adjusted and fixed to any portion of said spindle 7 by means preferably of a screw q^1 ; 45 thus rendering it possible to adjust the position of said spring r on said key for varying thicknesses of doors.

The device for restricting the movement of the spindle key in and out of the lock body, comprises a pin n adapted to be received into groove 7^t in the spindle key 7 . Said pin n is attached by one end to a bearing n^1 shown in Figures 11 and 12. Contained in said bearing is or may be a plunger m^3 having a flange m^2 at one extremity and a head portion m for manipulating the spring-pressed device when required. Pin n lies in and passes through a hole j^5 in flange j^1 of shaft j , and its bearing n^1 and its plunger m^3 normally occupy a recess j^4 in said flange. This device is maintained in its normal position for restricting the inward and outward movement of the spindle key by means of a spring-pressed plunger having a spring-bearing portion n^3 and a plunger portion n^4 that normally leans against bearing n^1 and maintains said bearing and the pin n in normal rest position with the pin in engagement with the spindle key. The spring-bearing member n^3 of plunger n^4 lies in and is arranged to move in a recess j^8 in bearing a^5 on casing a . Member n^3 carries preferably a compression spring which is arranged to be compressed by plunger n^4 , when the restricting device $n—m$ is moved in a direction away from the spindle key. When said key restricting device is moved in said direction it causes plunger n^4 to move into recess j^8 and compress spring n^5 , the movement of the device being arrested when plunger n^4 moves entirely into recess j^8 . Bearing n^1 with its plunger m^3 would then occupy a position within recess j^7 in flange a^5 on the casing a . Should m be released, plunger n^4 under the impulse of spring n^5 will immediately return the restricting device to normal position. If it is desired however, to throw this restricting device out of operation or to throw the entire locking mechanism out of operation, 90 said device is moved to the above-mentioned position against the action of said spring n^5 , and plunger m^3 is then moved longitudinally in its bearing n^1 for delivering its flange m^2 into holes j^6 in casing a thus 95 preventing rotation of part j^1 . It is evident then that device $n—m$ has two functions—one for normally restricting the movement of said spindle key inwardly and outwardly, and secondly for rendering the locking mechanism inoperative even by the use of the proper key from the outside or the inside of the door. This added feature is an advantage when an apartment or house is locked up for the night—all the members of 100 the family at home, and it is desired to render the locking mechanism inoperative from the outside of the door even by the proper key.

In a modified type of spindle key, as 105 shown in Figures 9^A, 10^A and 11^A, the spring for automatically withdrawing the key a distance is attached to plate 21 fastened to the inner end of key plug K. Said spring 22 has preferably a slot 22^b through which 110 passes a spindle key sk , and which is not wide enough to admit spindle portion 7 of said key. To the end that when said key is moved full length into the tumbler barrel, shoulders 7^c bear against said spring and 115 cause the key to enter against its resistance. When the operation is completed, spring 22 bears against shoulders 7^c and moves the spindle key a distance out of the key plug 120 and thus locks said key plug.

125

In Figure 15^a is shown a modified type of device for rendering the locking mechanism inoperative. It comprises a pin 32 adapted to move into a hole 33 in shaft 6; 5 said pin being attached to a slide member 31, to which is attached a push member 30 passing through and adapted to slide in a slot in the casing 1. When it is required to throw the locking mechanism out of operation, pin 32 is moved into hole 33 in shaft 6.

The above-described types of locks are preferably used in connection with my improved keeper, wherein M represents the mortise plate, LS the rim plate, B the machine screws for fastening the two plates to a door jamb or mate door, and W designates a wood screw for fastening the leg of said keeper to said jamb.

The operation of the lock is as follows:

- 20 A pin key inserted into the tumbler barrel from the outside unlocks said tumbler barrel in the usual manner. Then upon rotation of said tumbler barrel by said key, shaft *j* is caused to operate cam *h* for actuating the bolts in the preferred type in the above-described manner. For performing the locking operation the key is turned in one direction and for unlocking said key is turned in the reverse direction. For unlocking the door, cam *h* is caused to move revolvably in a direction opposite to that indicated by arrows in Figure 1. Stud *h*² in said cam *h* forces actuator bolt *d* to return wholly within the casing, and to simultaneously move the hooked bolt *c* out of its engaging position. Said stud *h*² now leaves groove *d*² in actuator bolt *d*, and as the cam continues in its revolvble movement, it dogs the hooked bolt in its locking position by 40 leaning against stud *c*⁵ in the hooked bolt *c*. Then stud *h*³, re-entering groove *c*⁴ in the hooked bolt, said hooked bolt is moved into its unlocking position during the completion of the revolvble movement of the cam *h*, and 45 is maintained in that position by said cam—stud *h*³ lying normally within groove *c*⁴, and preventing movement of said hooked bolt out of the casing except by the instrumentality of said cam.
- 50 To operate the locking mechanism from the inside by means of the spindle key, the restricting device *n—m* is disengaged from the spindle key, then the key is moved into the lock body as far as it will go against the resistance of the spring *r* attached to slide *q*. Then upon rotation of said tumbler barrel, which has been unlocked by said spindle key, shaft *j* is caused to rotate and operate the cam for actuating the locking mechanism in the above-described manner. Upon releasing of device *n—m*, and upon release of the spindle key, spring *r* on slide *q* will automatically withdraw said spindle key a distance, said spring pressed device 65 will move automatically into engagement

with said spindle key, pin *n* being received into groove *7*^t in said key for restricting the movement of said key in a direction inwardly and outwardly.

When required, the device *n—m* is pressed back and spindle key *7* is entirely withdrawn from the lock body for the purposes above-described, and if it is desired to allow of the operation of the locking mechanism from the outside after so withdrawing the spindle key, said device *n—m* is allowed to return to its normal rest position under the impulse of its spring. Should it be desired, however, to render the locking mechanism inoperative from the outside, said device *n—m* is pressed back completely, and plunger *m*³ is moved longitudinally in bearing *n*¹ for delivering flange *m*² into hole *j*⁶ in casing *a*. This tends to lock shaft *j* against revolvble movement and thus prevents operation of the locking mechanism when tumbler barrel *K* is unlocked by the proper key. To render the locking mechanism operable, flange *m*² is withdrawn from hole *j*⁶ in the casing and device *n—m* is allowed to return to normal position under the impulse of its spring *n*⁵.

Having thus fully described the invention what I claim as new and desire to secure by Letters Patent, is:

1. In a lock, the combination of an actuator and a hooked bolt connected together for longitudinal movement relatively to each other, means for moving said hooked bolt and for subsequently causing said actuator to move in a direction for projecting the hooked bolt into engaging position, and to then move said actuator into its extreme operative position and into supporting relation with reference to said hooked bolt.

2. In a lock, the combination of an actuator and a hooked bolt connected together for longitudinal movement relatively to each other, means for moving said hooked bolt longitudinally and for subsequently causing said actuator to move said hooked bolt into engaging position and to then cause said actuator to move into its extreme operative position to dog said hooked bolt in such position.

3. In a lock, the combination of a hooked bolt with an actuator bolt connected together for longitudinal movement relatively to each other, means for moving said hooked bolt and for subsequently moving said actuator bolt in a direction for primarily projecting the hooked bolt into engaging position and to then move said actuator bolt into closure locking position, for locking said hooked bolt in said projected position.

4. In a lock, the combination of a hooked bolt with an actuator bolt, connected together for longitudinal movement relatively to each other, said actuator bolt being normally wholly confined within the casing, and means for moving said hooked bolt and to

subsequently cause said actuator bolt to move said hooked bolt into engaging position and to then move said actuator bolt into closure locking position to dog the hooked bolt in 5 its engaging position, said actuator bolt being arranged to move its locking projection out of the casing when moved by said means into locking position.

5. In a lock, the combination of a hooked 10 bolt with an actuator bolt, and a cam for moving said hooked bolt and for subsequently causing said actuator bolt to move first in a direction for moving the hooked bolt into engaging position and then to move 15 into closure locking position, independently of said hooked bolt and in supporting relation with reference to said hooked bolt.

6. In a lock, the combination of an actuator bolt with a hooked bolt connected together 20 for longitudinal movement relatively to each other, said actuator bolt being normally wholly confined within the casing, and a cam for moving the hooked bolt and for subsequently forcing said actuator bolt to 25 project said hooked bolt into engaging position, and to then move said actuator bolt independently of said hooked bolt into closure locking position to deliver a locking projection thereof out of the casing and to 30 dog the hooked bolt in its engaging position.

7. In a lock, the combination of a hooked bolt and an actuator bolt connected together for longitudinal movement relatively to each other, said actuator bolt being normally 35 wholly confined within the casing, and a cam for moving the hooked bolt, said cam acting to prevent reverse movement of said hooked bolt, and subsequently thereto for actuating said actuator bolt and for causing said actuator 40 bolt to move said hooked bolt into engaging position, and then delivering said actuator bolt into closure locking position and in supporting relation with reference to said hooked bolt.

45 8. In a lock, the combination of a hooked bolt with an actuator bolt connected together for longitudinal movement relatively to each other, and a cam for moving said hooked bolt on said actuator bolt and individually of said actuator bolt, and subsequently thereto for moving said actuator bolt on said hooked bolt and individually of said hooked bolt for moving said hooked bolt in a direction to deliver said hooked 50 bolt into engaging position, and then delivering said actuator bolt into a position for dogging said hooked bolt in its engaging position.

55 9. In a lock, the combination of a hooked bolt with an actuator bolt connected together for longitudinal movement relatively to each other, and a cam for moving said hooked bolt longitudinally and to dog said bolt in 60 said position, and subsequently thereto for causing said actuator bolt to move in a di-

rection for moving the hooked bolt into engaging position and for then moving said actuator bolt into a position for maintaining said hooked bolt against reverse movement from its engaging position. 70

10. In a lock, the combination of a hooked bolt and an actuator bolt connected together for longitudinal movement relatively to each other, said hooked bolt being adapted to move longitudinally in and out of the casing, means for guiding the longitudinal movement of said hooked bolt in and out of the casing, said means being adapted to prevent vertical movement of said hooked bolt during its longitudinal movement, said 75 guiding means being arranged to allow of said vertical movement of said hooked bolt when said bolt is moved into locking position prior to being moved into engaging position, and a cam for moving said hooked bolt into locking position and for subsequently actuating said actuator bolt for primarily causing the hooked bolt to move into engaging position and then delivering said actuator bolt into locking position to prevent reverse 80 movement of said hooked bolt from its engaging position except by the instrumentality of said cam.

11. In a lock, the combination of a hooked bolt with an actuator bolt connected together 95 for longitudinal movement relatively to each other, a cam for moving said hooked bolt and for subsequently actuating said actuator bolt for the purposes to cause said actuator bolt to move in a direction for projecting 100 said hooked bolt and then to move said actuator bolt into a position partly outside the casing, means being provided for guiding said actuator bolt.

12. In a lock, the combination of a hooked 105 bolt with an actuator bolt, a cam for moving said hooked bolt and for subsequently moving said actuator bolt for projecting the hooked bolt into engaging position and for then delivering said actuator bolt into locking position, means for actuating said cam, 110 said cam acting to prevent reverse movement of said actuator bolt and thereby said hooked bolt from its engaging position except by the instrumentality of said means. 115

13. In a lock, the combination of an actuator bolt with a hooked bolt, said bolts being connected together for longitudinal movement relatively to each other, a longitudinal slot in said hooked bolt terminating 120 in a substantially vertical slot, a shaft and a cam thereon, said cam having two elements, one of said elements engaging the hooked bolt, and the other element subsequently engaging the said actuator bolt, 125 both of said elements to successively actuate said bolts and to prevent the return of said bolts except by the reverse movement of said cam.

14. In a lock, the combination of a hooked 130

- bolt with an actuator bolt, said bolts being connected together for longitudinal movement relatively to each other, an opening in said hooked bolt allowing of its movement 5 in two directions, a shaft running through said opening, a cam upon said shaft, said cam having two elements, one of said elements engaging the hooked bolt and the other of said elements subsequently engaging 10 the actuator bolt, said element engaging with a hooked bolt actuating said hooked bolt when the cam is operated, and the element engaging with the actuator bolt actuating said actuator bolt subsequently to the 15 operation of said other element for moving said hooked bolt in another direction and to lock said hooked bolt in such position.
15. In a lock, the combination of one element having a locking projection with 20 another element having a locking projection, said elements having means connecting them together for longitudinal movement relatively to each other, an opening in one of said elements allowing of the movement 25 of that element in two directions, a shaft passing through said opening, a cam upon said shaft, means on said cam to engage with one of said elements for moving said element in one direction, and additional 30 means on said cam to subsequently engage said other element to cause said other element to move the previously actuated element in a second direction, and to then move said other element into closure locking 35 position to lock said previously actuated element against reverse movement from the position to which it had been delivered except by the reverse movement of said other element.
- 40 16. In a lock, the combination of a first element having a locking projection with a second element having a locking projection, said elements being connected together for longitudinal movement relatively to each 45 other, an opening in said first element allowing of its movement in two directions, means for guiding its movements in said directions, means on said second element co-acting with means on the lock casing for 50 guiding the movement of said second element in two directions, a shaft passing through said opening in said first element, a cam upon said shaft, means associated with said cam to engage with said first element 55 for moving said element in one direction, and additional means upon said cam to subsequently engage with said second element for moving said element along its guides in a direction to cause said first element to 60 move into engaging position, and to lock said first element in such position.
- 65 17. In a lock, the combination of two elements each having a locking projection and connected together for longitudinal movement relatively to each other, revolute
- means for impelling one of said elements translationally in one direction, and for subsequently forcing the other of said elements to impel the previously actuated element translationally in another direction, and 70 means for operating said revolute means forward and reversely to move both of said elements successively into closure locking position and to withdraw same.
18. In a lock, the combination of a lock 75 casing having studs and grooves, a hooked bolt movable in and out of said casing, an actuator bolt having a locking projection and connected with said hooked bolt for longitudinal movement relatively to each 80 other, said studs on the casing being arranged to guide the movements of said hooked bolt, studs on said actuator bolt adapted to be taken into said grooves on said lock casing for guiding the movements 85 of said actuator bolt, and revolute means for moving said hooked bolt individually on said actuator bolt translationally in one direction, and for subsequently moving said actuator bolt individually on said hooked 90 bolt for moving said hooked bolt translationally in another direction, and delivering said actuator bolt into locking position to dog said hooked bolt, and means for operating said revolute means forward and reversely to move said bolts in the above manner 95 and to withdraw said actuator bolt and cause said actuator bolt to withdraw the hooked bolt from its engaging position to finally allow of the withdrawal of said hooked 100 bolt by said revolute means to unlocking position.
19. In a lock, the combination of a hooked bolt with an actuator bolt connected together for longitudinal movement relatively 105 to each other, means guiding the movement of said hooked bolt translationally in two directions, additional means guiding the movement of said actuator bolt translationally in two directions, a shaft, a cam thereon, a pair of studs in said cam, one of which engages the hooked bolt, and the other of which studs subsequently engages the actuator bolt, both of said studs to actuate said bolts in the manner and for the purposes 110 herein substantially described, and to prevent the return of said bolts except by the reverse movement of said cam.
20. In a lock, the combination of a hooked bolt and an actuator bolt, a shaft, a cam 115 upon said shaft, a pair of studs in said cam, one of which engages the hooked bolt, and the other of which subsequently engages the actuator bolt, the one of said studs to move said hooked bolt translationally in one 120 direction, and the other of said studs to subsequently cause said actuator bolt to move the hooked bolt translationally in another direction and to prevent the return thereof except by the reverse movement of said cam. 125
- 130

21. In a lock, the combination of a hooked bolt and an actuator bolt connected together for longitudinal movement relatively to each other, a shaft, a cam thereon, a stud in said bolt, a pair of studs in the cam, one of said studs normally engages the hooked bolt, the other of said studs subsequently engages the actuator bolt when the previously actuating stud is disengaged from said hooked bolt, both of said studs to successively actuate their respective bolts, said hooked bolt stud acting to prevent the return of said hooked bolt while it is in engagement with said hooked bolt except by the reverse movement of said cam, and said cam acting to prevent the return of said hooked bolt subsequently to the release thereof by said stud in the cam which then continues to lean against said stud on the hooked bolt during the completion of its revoluble movement, and said stud for actuating the actuator bolt acting to prevent the return of said actuator bolt and of the hooked bolt except by the reverse revoluble movement of said cam.
22. In a lock, the combination of a lock casing, irregular shaped grooves in the casing, a hooked bolt and an actuator bolt connected together for longitudinal movement relatively to each other, said actuator bolt having studs adapted to be taken into said grooves in the casing, one stud in each groove, and a cam for moving said hooked bolt translationally in one direction, and for subsequently actuating said actuator bolt to cause it to be guided by its studs in a direction for moving said hooked bolt into engaging position and then to move into locking position to prevent the return of said hooked bolt from its engaging position except by the reverse movement of said cam.
23. In a lock, the combination of a hooked bolt adapted for slidable and pivotal movement and a cam for moving said hooked bolt and for subsequently projecting said bolt into engaging position.
24. In a lock, the combination of a cam and a hooked bolt adapted for slidable and pivotal movement, said cam to move said hooked bolt and subsequently project said bolt into engaging position, and prevent the return thereof except by reverse revoluble movement of said cam.
25. In a lock, the combination of a hooked bolt adapted for slidable and pivotal movement, a shaft, a cam thereon for moving said hooked bolt and for subsequently projecting said bolt into engaging position and to dog said bolt in such position.
26. In a lock, the combination of a hooked bolt adapted for slidable and pivotal movement, a shaft, a cam thereon, a pair of elements connected to said cam, one of which engages with said bolt to move said bolt translationally in one direction, and the other of which engages with said bolt subsequently to move said bolt subsequently translationally in another direction, the said elements and the cam being adapted to prevent return of said bolt except by the reverse movement of said cam.
27. In a lock, the combination of a hooked bolt adapted for slidable and pivotal movement, a slot in said bolt, a shaft taking into said slot, a cam upon said shaft, means for rotating said shaft to operate said cam for moving said bolt longitudinally along said shaft as a guide and for subsequently moving said bolt into engaging position on said shaft as a pivot, and to dog said bolt in said engaging position.
28. In a lock, the combination of a hooked bolt, a slot in said bolt, a shaft taking into said slot, a cam upon said shaft, a stud in said cam normally in engagement with said bolt, and a projection on said cam normally not in engagement with said bolt, and means for rotating said shaft and operating said cam to cause said stud in the cam to move said bolt translationally in one direction, said stud acting to prevent reverse movement of said bolt during said translational movement and adapted to be disengaged from said bolt subsequently to said movement, the cam in continuing its revoluble movement then acting to prevent the return movement of said bolt except by reverse movement of said cam, and to finally cause said projection on the cam to engage with and move said bolt in another direction and to dog said bolt in such position.
29. In a lock, the combination of a hooked bolt, means restricting its movement longitudinally, means restricting its movement vertically, a slot, a groove and a stud in said bolt, a shaft passing through said slot in the bolt, a cam upon said shaft, a stud in said cam and a projection on said cam, and means for operating said cam to cause said stud in the cam to move in and out of said groove in the bolt for moving said bolt, and then continuing the revoluble movement of said cam to cause said cam to constantly lean against said stud in the bolt for preventing reverse movement of said bolt except by reverse movement of said cam and finally to deliver said projection on said cam into engagement with said stud in the bolt for projecting said bolt into engaging position and to dog said bolt in such position, reverse movement of said cam being prevented except by operation of the means for operating said cam.
30. In a lock, the combination of a bolt having a plurality of hooked bolts on its outer or locking end with an actuator bolt, and means for moving said multiple hooked bolt translationally in one direction, and subsequently causing said actuator bolt to move said multiple hooked bolt translationally in another direction and to prevent re-

turn movement of said actuator bolt and said multiple hooked bolt except by reverse movement of said means.

31. In a lock, the combination of a plurality of connected hooked bolts with an actuator bolt, said actuator bolt and said connected hooked bolts being connected together for longitudinal movement relatively to each other, means for moving said connected hooked bolts into locking position, and subsequently actuating said actuator bolt for moving said connected hooked bolts into engaging position and to lock said hooked bolts against reverse movement except by the reverse movement of said actuator bolt, said means being adapted to prevent return of said actuator bolt except by reverse movement of said means.

32. In a lock, the combination of a bolt having a plurality of hooked bolts on its outer end, and an actuator bolt connected with said multiple hooked bolt for longitudinal movement relatively to each other, means for guiding the movement of said multiple hooked bolt in translationally two directions, and a cam for moving said multiple hooked bolt translationally in one direction and subsequently to move said actuator bolt in a direction for moving said multiple hooked bolt translationally in another direction, and then delivering said actuator bolt into locking position to prevent return movement of said multiple hooked bolt except by reverse movement of said actuator bolt, said cam being arranged to prevent reverse movement of said actuator bolt except by reverse revoluble movement of said cam.

33. In a lock, the combination of a multiple hooked bolt with an actuator bolt connected together for longitudinal movement relatively to each other, a slot in said multiple hooked bolt, a shaft taken into said slot, a cam upon said shaft, a pair of elements in said cam, one of which engages said multiple hooked bolt to move said bolt translationally in one direction, and the other of which subsequently engages said actuator bolt to force said actuator bolt to move the multiple hooked bolt translationally in another direction and then to deliver said actuator bolt into locking position to prevent the return movement of said multiple hooked bolt except by reverse movement of said actuator bolt, and to prevent reverse movement of said actuator bolt except by reverse movement of said cam.

34. In a lock, the combination of a plurality of connected hooked bolts, a shaft, a cam thereon, and means for operating said cam to cause said cam to move said bolts on said shaft as a guide and for subsequently projecting said bolts into engaging position on said shaft as a pivot and to prevent the return of said bolts from said projected po-

sition except by reverse movement of said cam, reverse revoluble movement of said cam being prevented except by the operation of said means.

35. In a lock, the combination of a locking mechanism, means for actuating said locking mechanism, key operated mechanism for operating said actuating means, and a spindle key arranged to operably connect said key mechanism with said actuating means, to operate said actuating means.

36. In a lock, the combination of a rotatable tumbler barrel and a rotatable cylinder connected together for longitudinal adjustment relatively to each other, a keyway in said rotatable cylinder in alinement with a keyway in said tumbler barrel, and a spindle key normally operably connecting said tumbler barrel with said cylinder, said spindle key being movable longitudinally in said keyways for unlocking and operating said tumbler barrel to allow of the operation of said rotatable cylinder.

37. In a lock, the combination of a tumbler barrel having a keyway and a rotatable cylinder having a keyway in alinement with said keyway in the tumbler barrel, said tumbler barrel and said cylinder being connected together for longitudinal adjustment relatively to each other, and a removable spindle key movable longitudinally in said keyways for unlocking said tumbler barrel to allow of the operation of said tumbler barrel and of said cylinder, means being provided for normally restricting the longitudinal movement of said spindle key into and out of said tumbler barrel keyway.

38. In a lock, the combination of a locking mechanism, means for actuating said locking mechanism, a rotatable cylinder, a tumbler barrel, said tumbler barrel and said cylinder being connected together for longitudinal adjustment relatively to each other, a keyway in said cylinder in alinement with a keyway in the tumbler barrel, and a removable spindle key movable longitudinally in said keyways for unlocking and operating said tumbler barrel to allow of the operation of said rotatable cylinder and said actuating means, means being provided for normally restricting the movement of said spindle key into and out of said tumbler barrel.

39. In a lock, the combination of a rotatable key plug, a rotatable cylinder, said key plug and said cylinder being connected together for longitudinal adjustment relatively to each other, said tumbler barrel being adapted to rotate said cylinder, and having a keyway in alinement with a keyway in said cylinder, locking mechanism, and means upon said cylinder for actuating said mechanism, and a spindle key longitudinally movable in said cylinder and said

rotatable key plug for unlocking said key of the door not controlled by said spindle key, an adjustable slide carrying a plug and rotating said rotatable cylinder spring being attached to said spindle key for for operating said actuating means.

40. In a lock, the combination of a rotatable key plug having a keyway and a rotatable cylinder having a keyway in alignment with said other keyway, and a removable spindle key for operating said rotatable key plug to allow of the operation of said 5 rotatable cylinder, means associated with said spindle key for restricting its movement into and out of said key plug, and means for automatically withdrawing said spindle key from said key plug a distance 10 to allow of the locking of said key plug for preventing operation of said key plug from that side of the door not controlled by said spindle key except by the proper key.

41. In a lock, the combination of a rotatable key plug and a rotatable cylinder connected together for longitudinal movement relatively to each other, connecting keyways in said plug and cylinder, and a spindle key normally contained in said keyways but removable therefrom, said spindle key being movable longitudinally within said keyways for unlocking said key plug and operating said cylinder, a spring-pressed device being provided for restricting the movement of said key into said key plug to a distance insufficient for unlocking said key plug, and to a distance out of said key plug to a distance to allow of the insertion of a key into said key plug from the 25 side of the door not controlled by said spindle key for operating the key plug from that side, and additional means associated with said spindle key for automatically withdrawing said spindle key a distance 30 from said key plug to relock said plug and prevent operation thereof by means other than the proper key from the side not controlled by said spindle key.

42. In a lock, the combination of a rotatable key plug and a rotatable cylinder connected together for longitudinal adjustment relatively to each other, connecting keyways in said plug and cylinder, and a removable spindle key normally contained within said 45 keyways and extending a portion of said key beyond the lock body for manipulation of said key, said spindle key being movable longitudinally into said key plug for unlocking and operating said plug and said cylinder, and removable from said plug a distance to allow of the relocking of said plug and said cylinder, and a spring-pressed device normally in engagement with said key for restricting its movement into said 50 key plug to a distance short of unlocking said key plug, and to a distance out of said key plug sufficient to allow of the operation of said key plug by means of the proper key from that side

of the door not controlled by said spindle key, an adjustable slide carrying a spring being attached to said spindle key for automatically withdrawing said key from the rotatable key plug a distance to allow of the relocking of said key plug and of said 65 70 cylinder.

43. In a lock, the combination of a rotatable key plug and a rotatable cylinder in operative connection with each other and having keyways in alignment with each other, 75 and a removable spindle key normally lying in said keyways and movable longitudinally therein for unlocking said key plug and operating said cylinder, a spring-pressed pin normally engaging said key for restricting 80 the movement of said key in and out of said key plug as substantially described and for the purposes designated, means in operative connection with said spring-pressed pin for disengaging said pin from said key to allow 85 of the movement of said spindle key into said rotatable key plug a sufficient distance for unlocking and operating said key plug and operating said cylinder, and a slide adjustable on said spindle key and carrying a 90 spring for automatically withdrawing said key a distance from said key plug to allow of the relocking of said key plug and to allow of the re-engagement of said spring-pressed pin with said spindle key. 95

44. In a lock, the combination of a rotatable key plug and a rotatable cylinder in operative connection with each other, and having alining keyways, a removable spindle key normally lying in said keyways and 100 movable longitudinally therein for unlocking and operating said key plug and thus said cylinder, a portion of said key projecting from the lock body for manipulation of said key, and a spring-pressed mechanical device normally in engagement with said spindle key for restricting the movement of said key into said rotatable key plug to a distance short of unlocking said key plug and outwardly to 110 a distance allowing of the insertion of a key for the operation of said key plug from that side of the door not controlled by said spindle key, said spring-pressed device embracing means allowing of 115 the manual disengagement of said device from said spindle key to allow of the full insertion of said key into said key plug for unlocking said plug, said means being adapted to engage with the lock casing to 120 render said rotatable shaft and thereby the locking mechanism inoperative, when required, and a spring adjustable upon said spindle key for withdrawing said key from said key plug a distance to allow the relocking of said key plug and for delivering 125 said key again into engagement with said spring-pressed mechanical device.

45. In a lock, the combination of a rotatable key plug and a rotatable cylinder, a spindle key for unlocking of said key plug and operating said cylinder, and a spring-pressed mechanical device for restricting the movement of said key in and out of the key plug for the purposes and in the manner described, said device being further adapted to throw the locking mechanism out of operation when it is not restricting the movement of said key, and comprises a pin movable in a hole in said cylinder, a bearing attached to said pin, a plunger movable longitudinally in said bearing and having a member for manipulating said device, and a spring-pressed plunger bearing against said bearing for maintaining said pin in normal position in engagement with said key when desired, and being manually disengageable from said key against the action of said spring-pressed plunger, and said plunger in the bearing being movable into a bearing in the casing when required for locking said rotatable cylinder against revoluble movement and to render the locking mechanism inoperative from the inside or outside.
46. In a lock, the combination of a rotatable key plug and a rotatable cylinder having alining keyways, and a spindle key op- erably connecting said key plug with said cylinder and movable longitudinally in said keyways for operating said key plug and said cylinder, means being provided for preventing complete removal of said key from said key plug, and means for restricting the movement of said key into said key plug and a spring-pressed device for withdrawing automatically said key from said plug a distance sufficient to allow of the locking of said key plug and prevent operation of said plug from the side opposite to that controlled by said spindle key except by the proper key.
47. In a lock, the combination of a rotatable key plug and a rotatable cylinder, and a spindle key for unlocking and operating said key plug and said cylinder from one side of the locking body, and a device for throwing said rotatable cylinder out of operation and thereby preventing the operation of said key plug and the locking mechanism.

Signed at New York, in the county of New York and State of New York this 8th day of September 1920.

ALEXANDER BLOCK.
